STRAINER AND COVER FOR PAILS.

Application filed July 10, 1926. Serial No. 121,640.

This invention relates to strainer and cover constructions for receptacles. Although the invention is capable of use in connection with various types of containers, it is particularly adapted for use in connection with milk pails, during the milking operation and during the process of treating the milk after the same has been taken from the cows.

10 It is an object of this invention, therefore, to provide an improved strainer and cover for receptacles.

15 It is more specifically an object of this invention to provide such a strainer and cover which may be adjustable to fit receptacles of different sizes.

20 Still another object of the invention is to provide a strainer and a cover adapted to fit the tops of various sized pails having upwardly flaring surfaces.

25 These and other objects of the invention will more fully appear from the following description made in connection with the accompanying drawings, wherein like characters refer to the same or similar parts throughout the several views, and in which

Fig. 1 is a perspective view of the device applied to a pail, a portion of the pail being broken away;

30 Fig. 2 is a view in side elevation of the outer band of the strainer with its ends disconnected;

Fig. 3 is a similar view of the inner band;

35 Fig. 4 is a vertical section of the inner band taken on the line 4-4 of Fig. 1; and

Fig. 5 is a vertical section of the outer and inner bands taken on the line 5-5 of Fig. 1.

40 In the drawings, an upwardly flaring pail 6 of standard construction is illustrated having an outwardly extending roll 7 formed at its upper end, a bale 8 and ears 9 to which the bale is secured. An arcu-

45 ately shaped strip 10 composed of flat resilient sheet material is provided having a plurality of spaced apertures 10^a shown as substantially horizontally extending slots formed adjacent one end thereof and a

50 tongue 10^b at its other end formed as shown by cutting a slot partially across the strip adjacent the end 10^b. The upper edge of strip 10 has a roll 10^c formed thereon extending from one end of the strip to within a short distance from the other end thereof.

A stiffening rod 10^d is secured in the roll 10^c and projects outwardly therefrom at one end and terminates short of the other end of the roll. An arcuate strip 11, also composed from flat resilient sheet material, is provided, having spaced apertures 11^a adjacent one end, shown as being substantially transverse slots, and a projecting tongue 11^b at its other end, the tongue 11^b being shown as projecting longitudinally from the end of the strip 11.

55 Strip 10 being of resilient material may be circularly bent as shown in Fig. 1; the tongue 10^b may be upwardly bent to the dotted position shown in Fig. 5, and the tongue engaged with any one of the apertures 10^a, the projecting end of the stiffening rod 10^d fitting within the opposite end of the roll 10^c as the two ends of the strips are joined. It can be seen that by placing the 60 tongue 10^b in the different apertures 10^a the diameter of the band or ring formed by the strip 10 when the ends are joined may be considerably varied. The two ends of the strip may be rigidly secured together by 65 bending the tongue 10^b downwardly from the dotted position, as shown in Fig. 5, to the position of the tongue shown in full lines in Fig. 5. The ends of strip 10 having been joined to form a band of suitable diameter, 70 the same may be placed with its outer surface against the inner surface of a container or pail such as the pail 6, the roll 10^c of the band abutting the roll 7 of the pail, or if no 75 roll or bead is provided on the pail, the roll 10^c abutting the top edge of the pail. Due to the arcuate formation of the strip 10, as 80 the ends of the same are joined to form a band, the band will be given an upwardly flaring shape so that the whole outer surface 85 of the band will contact the inner surface of the pail adjacent the top thereof. The strip 10 will form the outer band of the strainer and cover.

85 The ends of the strip 11 may now be joined by curving the strip to form a rough circle and inserting the tongue 11^b in one of the apertures 11^a, the outer diameter of the inner band so formed being made by proper adjustment of the tongue 11^b in the apertures 11^a to approximately equal the inner diameter of the outer band 10. The ends of the strip 11 may be secured by bending the tongue 11^b to the dotted position shown in Fig. 4, inserting the tongue in one of the 90 95 100 105 110

apertures 11^a and reversely bending the tongue to the position shown in full lines in Fig. 4.

The strainer member 12 composed preferably from a flexible sheet of woven mesh material is placed to extend somewhat below the outer band 10 with portions thereof contacting the sides of the band at all points on its lower inner circumference. The inner band 11 may now be inserted within the outline of the outer band 10 on top of the portions of the flexible sheet member 12 which contact the inner surfaces of the outer band, and the co-operating inner surface 15 of the outer band and the outer surface of the inner band will securely clamp the straining member 12 in operative position. The band 11 being formed from an arcuate strip will have upwardly flaring surfaces so that the outer sides of the band will closely conform to the inner surface of the outer band. The strainer and cover may be assembled before or after the outer band is positioned on a receptacle or pail, but is 20 preferably assembled before the outer band is seated on the receptacle.

If desired, either or both of the tongues 10^b and 11^b instead of being first outwardly bent from the main body portions of the bands as the ends of the two bands are 30 joined, may be inwardly bent. The ends of the bands will then be joined at opposite sides thereof from the joined sides shown in the drawings. The position of tongue 10^b adjacent the end of the band 10 may be varied if desired. Various types of apertures and tongues may be formed on the strips 10 and 11 by which the ends of the strips may be secured together.

The device when applied to a pail will provide a strainer which can be used at the time a cow is milked to strain the milk and keep all sediment falling from the cows and otherwise blowing about from falling into the milk. If the milk from the cow is 45 bloody or gargety, this will be indicated on the strainer member. The quality of the milk will accordingly be increased by use of the present invention, as sediment that would otherwise fall into the pail would dissolve to a certain extent in the milk and the value of the milk would accordingly be decreased. There will be no opportunity for the milker to get his hands into the pail while the cows are being milked, and accordingly drier and 50 cleanlier milking will be accomplished. The strainer and cover will not get in the way of the milking operation.

Preferably cheese-cloth is used for the 60 straining member 12 and this cloth can be readily removed for cleaning by simply disassembling the two bands 10 and 11 and lifting the straining member 12 from the outer band whereupon the same may be readily washed. If wire mesh is used for the strain-

ing member 12, this can also be readily removed for cleaning.

The device can be quickly fitted to be placed on pails or receptacles of various sizes or shapes.

It is now customary to cool milk immediately after milking either before or after the same has been run through a separator. This cooling process is usually accomplished by allowing the pails of milk to stand in 70 cold water for some length of time and allowing milk to be exposed to the air to take out all the animal heat from the milk. With the present device the pails may be conveniently placed in water and the device will 75 provide a cover over the pails which will prevent the milk from becoming fouled and yet will permit the access of air to the milk.

The device will also have high utility for use in other connections than in milking or 80 in treating milk.

It will, of course, be understood that various changes may be made in the form, details, arrangements and proportions of the various parts without departing from the 90 scope of the present invention which, generally stated, consists in the matter shown and described and set forth in the following claims.

What is claimed is:

1. A strainer and cover for a pail comprising circumferentially adjustable outer and inner bands and a flexible sheet member clamped between said bands, each of said bands having a plurality of apertures 100 adjacent one end and variably spaced therefrom and a tongue adjacent its other end adapted to be secured in any of said apertures.

2. A strainer for a pail comprising an 105 outer ring formed from an arcuate strip of resilient material, said strip having an outwardly extending roll at its top edge, said roll extending from one end to adjacent the other end of said strip, a stiffening rod secured in said roll and having one end projecting from one end of said roll, and adapted to fit within the other end of said roll when the ends of said strip are joined, said strip having a plurality of apertures at one 110 end thereof, and a tongue adjacent the other end thereof, said tongue being adapted to be secured in any one of said apertures, an inner ring formed from an arcuate strip of 115 resilient material having apertures adjacent one end and a tongue at the other end thereof, said tongue being adapted to be secured in any one of said apertures to form a ring having an outer circumference of such size as to closely fit against the inner 120 side of said outer ring, and a strainer member of flexible woven mesh adapted to be clamped between the sides of said rings.

3. A strainer and cover for annular containers, comprising a pair of arcuately 125

shaped strips formed from flat resilient material, said strips being respectively adjustably securable adjacent their ends to form upwardly flaring bands, the outer surface of

5 one of which is adapted to closely engage the inner surface of the other and a flexible member of woven mesh adapted to be clamped between said bands, the outer flar-

ing surface of the second mentioned band being adapted to closely engage the inner 10 surfaces of upwardly flaring annular containers.

In testimony whereof we affix our signatures.

ELLERTH C. OVERBOE.

MELVIN I. GRESETH.
